UNITED STATES PATENT OFFICE.

EDWARD H. MILLER, OF INDIANAPOLIS, INDIANA, ASSIGNOR TO
NATIONAL STRAW BINDER AND MACHINE CO., OF INDIANAPOLIS, INDIANA, A CORPORATION OF INDIANA.

GAME APPARATUS.

No. 824,879.

Specification of Letters Patent.

Patented July 3, 1906.

Application filed December 11, 1905. Serial No. 291,284.

To all whom it may concern:

Be it known that I, EDWARD H. MILLER, a citizen of the United States, residing at Indianapolis, in the county of Marion and State of Indiana, have invented certain new and useful Improvements in Game Apparatus, of which the following is a specification.

This invention relates to a game apparatus; and the object of the invention consists in the production of an apparatus by which the game of base-ball can mechanically be played on a miniature field and still be governed by the same rules and regulations that govern the national game.

The object consists, further, in a game apparatus for playing base-ball in which all the parts are automatically operated, giving each player an equal opportunity of scoring the points and still retain those uncertainties that must accompany a game to invoke interest and zeal.

I accomplish the objects of my invention by the mechanism illustrated in the accompanying drawings, in which—

Figure 1 is a perspective view of my game apparatus. Fig. 2 is a top or plan view of same. Fig. 3 is a longitudinal central sectional view of said game apparatus. Fig. 4 is an under side plan view of said game apparatus. Fig. 5 is a fragmentary detail perspective view of the operating-levers, the framework being omitted. Fig. 6 is a detail of one of the stirrups employed to form bearings for certain parts of the mechanism.

In the drawings, 1 represents the base of the game apparatus, and 2 denotes the field on which it is played. The boundary of the field is defined by means of the rib 3, that slightly projects above the level of the field 2 and is secured to the outer edge of the base 1. The base 1 is mounted on a slight incline, so that the balls when pitched will return to a given point.

The base 1 of the game apparatus is provided with an alley 4 at the side which is separated from the field 2 by means of the partition 6. The players place a ball 8 (see Fig. 1) in the alley 4, which is to be pitched into the field 2. The alley 4 guides the pitched ball against the circular portion of the rib 3 at the head of the field. The ball pitched from the alley 4 is called the "object-ball" and is employed by the players to automatically oper-

ate the mechanism of the game apparatus. The object-ball 8 (see Fig. 1) after leaving the 55 alley 4 hugs the rib 3 until it strikes the pin *a*, that stands vertically in the field 2 and near enough to the rib 3 to prevent the ball from passing between it and said rib. The pin *a* will deflect the course of the object ball 8, so 60 that to predetermine its course after leaving said pin would be mere speculation. The base of the apparatus 1 near its foot is provided with a plurality of rows of pins 12, which are arranged in a staggered manner, 65 so that the object-ball 8 after leaving the pin *a* will most likely strike one or more of them, and thus be still further deflected from its original course before it reaches the pockets at the foot of the base 1. It will be seen that 70 the course of the object-ball will be extremely irregular before reaching the pockets and is intended to prevent any undue advantages taken by a player through manipulation.

The base 1 is divided at its foot by the partition-walls 15, which form pockets to receive the spent object-balls. These pockets are named to indicate the plays, and an object-ball once pitched must be allowed to take its own course in traversing the field to 80 reach the pockets in order that an accurate score may be recorded.

Any number of persons that can be equally divided can participate in the game. An umpire should first be selected to register the 85 names of the opposing teams, to call the name of the players at their proper turn, and to keep the score. He must closely observe the object-ball when pitched to prevent any interference therewith and to announce the 90 result as indicated by the name on the pocket into which the ball drops. He should also record the balls and strikes against the players. For instance, should the object-ball drop into either of the pockets A or Q it 95 would indicate a "foul ball," but were it to drop into the pockets B, D, G, K, or M it would credit the batsman with a "ball," which would be a point in his favor, and if the ball had dropped into either of the pockets C, F, L, or O a "strike" would have been registered against the batsman, because three strikes would cause his retirement.

So far the description deals only with such plays that affect the batsman while standing at the home base while attempting to

make a safe hit, is charged with a foul, or strike, or be credited with a ball; but to enable the batter to move a base on a one-base hit or a two-base hit, &c., or permitting a base-runner to be advanced a base on a batsman's safe hit or to be able to steal a base brings into operation certain mechanism not heretofore set forth and which will now be described.

To accomplish the objects above set out, I provide a diamond 20, which is rectangular in shape and which is secured in a suitable manner to the base 1. The diamond 20 is placed in the center of the field and is built on an incline, so that the home base, which is indicated by means of the vertical pin 25, is at the highest point thereof. From the home base there is a gradual descent to the foot of the diamond, which is beneath the home base. First base is indicated by the pin 26, second base by the pin 27, and third base by the pin 28. The diamond 20 is provided with the groove 30, formed in its surface to provide a raceway for the ball 40, employed by the player to denote the batsman. (See Fig. 1.)

A plurality of the pockets at the foot of the base 1 are provided with an aperture 45, that passes through said base. Levers mounted on the under side of the base 1 engage the apertures 45. The levers also engage the vertical pins 25, 26, 27, and 28, which indicate the bases on the diamond 20, and in case the object-ball 8 should drop into one of the pockets that are provided with an aperture the lever engaging therewith would be actuated together with the coöperating levers. The arrangement of these levers is such that a base-runner will be permitted to move as many bases as the hit made by him is entitled. As an illustration, suppose the object-ball 8 should drop into the pocket I, the main "one-base-hit" lever I' would be actuated. This lever is pivotally mounted in the standard I², which is secured to the under side of the base 1. The front end of the main lever I' is bent to form a hook I³, that engages an aperture in the parallel counter-lever I⁴, which is pivotally mounted in the standard I⁵. The counter-lever I⁴ engages the vertically-extending home-base-indicating pin 25, which is movably mounted in and guided by the stirrup I⁶. The lever I⁴ is interposed between the main lever I' and the pin 25, so as to impart sufficient and proper movement to said pin. The pin 25 when actuated is lowered until its upper end disappears below the surface of the diamond 20, thus permitting the player's ball 40, which represents the batsman, to move to first base, at which point its movement is arrested by means of the pin 26, which represents first base. It may here be stated that had the object-ball dropped into the pocket H the main "two-base-hit" lever H' would have

been actuated. This lever is pivotally mounted in the standard H² and terminates at its forward end into a pin that engages an aperture in the coöperating transverse-extending lever H³, which is pivotally mounted in the standard H⁴. This lever engages the pin 26, which represents first base, and when actuated by the main lever H' the pin 26 is lowered. Examining Fig. 5 it will be seen that as the forward end of the main lever H' is elevated the forward end of the counter-lever I⁴ is also raised, and the other end, which engages the pin 25, will cause said pin to be lowered. The pins 25 and 26, being lowered, will permit the ball 40 to move from home base to second base, at which point further movement is prevented by the pin 27, that represents second base. The pin 26 is mounted in a stirrup H⁶, which is similarly constructed to the stirrup I⁶, and, further, should the object-ball 8 have dropped into the pocket P instead of the pocket H the main "three-base-hit" lever P' would have been actuated. This lever is pivotally mounted in the standard P² and its forward end engages with the coöperating transverse-extending lever P³. This latter lever engages the vertical pin 27, that represents second base, causing said pin to be lowered. The lever P³ also imparts movement to the intermediate lever X, that is pivotally mounted in the standard Y. The lever X engages the transverse lever P³ at one end, while the other end supports the ends of the levers I⁴ and H³, which engage the vertical pin 25, that represents home base, and the pin 26, that represents first base, so that these latter levers will be actuated when the lever P³ is actuated. The pins 25, 26, and 27, being lowered below the runway 30, will permit the ball 40 to move from home base to third base, thus crediting the player with a three-base hit. The ball 40 will be arrested in its movement when reaching third base by the vertical pin 28, that represents said base, and, further, supposing the object-ball 8 should have dropped into the pocket J, the main "home-run" lever J' would have been actuated. This lever is pivotally mounted in the standard J² and at its forward end engages the transverse-extending lever J³, which is pivotally mounted in the standard J⁴. The lever J³ engages and operates the vertical third-base pin 28 at one end, while its other end supports and actuates, first, the intermediate lever X, that extends and engages the transverse lever P³, which is capable of actuating the third-base pin 28; second, the transverse lever H³, which is associated with the main lever H' to actuate the first-base pin 26; third, the counter-lever I⁴, which, associated with the main lever I', actuates the home-base pin 25. Thus, if the object-ball 8 actuates the main lever J', then by the associated levers the pins 25, 26, 27, and 28 will be lowered, so as to permit the ball 40 to

make a complete unobstructed circuit of the diamond 20 and the player will be credited with a home run. Attention is invited to the remaining levers B', C', and O', that connect with the pockets B, C, and O and to which no reference has yet been made. The functions of these levers are to assist in making plays peculiar to the game, and they will now be considered.

10 Supposing the object-ball 8 of the batsman dropped into the pocket C and at this time a succeeding batsman was occupying first base, secured by him on his safe hit, the main lever C' would be actuated, and through 15 its engagement with the associated transverse-extending lever C³, that engages the first-base pin 26, the latter would be lowered, thus permitting the runner occupying the base to move to second base. The runner 20 would be credited with a "stolen base," while the batter would be charged with a strike. Again, suppose second base was occupied by a base-runner and the batter's object-ball 8 should drop into the pocket B. The main lever 25 B', together with its associated transverse-extending lever B³, which engages the second-base pin 26, would be actuated, thus permitting the base-runner to move to third base. The base-runner in this instance, as in the 30 former, would be credited with a stolen base while the batter this time would be credited with a ball. The main lever O' and its associated lever O³, that engages the third-base pin 28, if operated by the object-ball 8, 35 would permit a base-runner occupying third base to move home, thus crediting the runner with a stolen base and charging the batter with a strike.

40 The various main levers and associated levers employed in my game apparatus are mounted so that the bulk of their weight will be on the side of the bearings opposite their raised ends in order to return and hold them in normal position after they have been operated.

45 Extending vertically through the raceway 30 of the diamond 20, midway between the home base and base No. 1, base No. 1 and base No. 2, and between base No. 2 and base 50 No. 3 are the pins 60, 61, and 62. These pins terminate in the movable rods 60^a, 61^a, and 62^a, which are secured at one of their ends to the under side of the game apparatus, while the other ends connect with the trans- 55 verse extending-levers B³, C³, and O³, which engage the base-indicating pins 26, 27, and 28. The object of these pins, which are situated in the path traveled by the ball 40, is to prevent two or more base-runners or balls 40 from accumulating on one base. Suppose 60 the first player should secure a base-hit, his ball 40 would be permitted to move to first base. The next player also secures a base- 65 hit, which entitles his ball to first base, and consequently some disposition must be made

with the runner already occupying first base. To prepare for such an emergency, I interpose the pin 60 between home base and first base, so that the second player's ball will engage said pin while moving to first base. The 70 weight of the ball 40 is sufficient to depress the pin 60, and as the pin is a part of the rod 60^a, that engages the transverse lever C³, which is positively engaged with the vertical first-base pin 26 the latter is also depressed. 75 The ball 40, occupying first base is permitted to move to second base when the pin 26 is depressed. As soon as the ball 40 has cleared the pin 60 it immediately rises, as does the connected first-base pin 26. The distance 80 between the home base and the first base is sufficient to permit the pin 26 to resume its normal position before the approaching ball 40 arrives. The pin 61 and its rod 61^a and the pin 62 and its rod 62^a perform similar 85 functions between the bases Nos. 1 and 2, and Nos. 2 and 3. The rod 61^a engages the transverse lever B³, which is capable of actuating the second-base pin 27, and the rod 62^a engages the transverse lever O³, which is capable of actuating the third-base pin 28. 90 No pin or rod is necessary between third base and home base.

Having thus fully described my said invention, what I desire to secure by Letters Patent is—

1. A base-ball field, an inclined rectangular-shaped raceway mounted within said field, movable play-indicating devices adapted to move along said inclined raceway, base-indicators forming stops for the play-indicating devices, and means for removing said stops from the path of said play-indicating devices.

2. A base-ball field, an inclined raceway within said field, movable play-indicating devices adapted to move along said raceway, base-indicating devices forming stops for the play-indicating devices, and means for removing said stops from the path of said play-indicating devices.

3. A base-ball field, an inclined raceway within said field, movable play-indicating devices adapted to move along said raceway, base-indicators forming stops for the play-indicating devices, and means for simultaneously removing two or more of said stops from the path of the play-indicating devices.

4. A base-ball field, an inclined geometrically-shaped raceway having four straight sides mounted within said field, movable play-indicating devices adapted to move on said raceway, base-indicators forming stops for the play-indicating devices, and means for removing said stops from the path of said play-indicating devices.

5. A base-ball field, an inclined raceway forming the diamond within said field, balls adapted to roll along the diamond and in said raceway, base-indicators forming ball-stops,

and means for removing said stops from the path of the balls.

6. A base-ball field, an inclined raceway forming the diamond within said field, play-indicating devices adapted to move along said raceway, base-indicators forming stops for the play-indicating devices, pockets formed across the foot of the ball-field, and movable actuators engaging both the pockets and base-indicators so that the latter may be operated from the former.

7. A base-ball field, an inclined raceway forming the diamond within said field, play-indicating balls adapted to roll along said raceway, pockets formed across the foot of the ball-field, and movable actuators engaging both the pockets and base-indicators so that the latter may be operated from the former.

8. A base-ball field, an inclined raceway forming the diamond within said field, play-indicating balls adapted to roll along said raceway, base-indicators forming ball-stops, pockets formed across the foot of the ball-field, deflecting-pins arranged in rows across the ball-field between the raceway and pockets, and movable actuators engaging both the pockets and base-indicators so that the latter may be operated from the former.

9. An inclined base-ball field, an inclined raceway within said field, movable play-indicating devices adapted to move along said raceway, movable base-indicators forming stops for the play-indicating devices, and means for actuating and removing said stops from the path of said play-indicating devices.

10. An inclined base-ball field, an inclined raceway within said field, movable play-indicating devices adapted to move along said raceway, base-indicators forming stops for the play-indicating devices, pockets formed at the foot of the ball-field, and movable actuators engaging both the pockets and base-indicators so that the latter may be operated from the former.

11. A base-ball field, an alley-way formed within said field, an inclined raceway forming the diamond within said field, movable play-indicating devices adapted to move along said raceway, movable base-indicators forming stops for the play-indicating devices, pockets formed across the foot of the ball-field, and movable actuators engaging both the pockets and base-indicators so that the latter may be operated from the former.

12. A base-ball field, an inclined rectangular raceway within said field, movable play-indicating devices adapted to move along said inclined raceway, base-indicators forming stops for the movable play-indicating devices, and means mounted between and con-

necting with the base-indicators, said means projecting into the path of the movable play-indicating devices to operate the base-indicators.

13. A base-ball field, an inclined raceway forming a diamond within said field, ball adapted to move along said raceway, movable base-indicating pins passing transversely of said raceway and forming ball-stops, ball-actuating means projecting into the path of the balls and interposed between ball-stops, to actuate the latter.

14. A base-ball field, an inclined raceway forming a diamond within said field, balls adapted to move along said raceway, movable base-indicating pins forming stops for the balls, movable actuators engaging the base-indicating pins, and a separable device traversing the ball-field and actuating said movable actuators and base-pins.

15. In a game apparatus described comprising a bounded field area, a raceway having terminals in different horizontal planes within said field area, movable base-indicators mounted at intervals along and transversely of said raceway when occupying normal position, but susceptible to movement away from said raceway, and movable actuators engaging and operating said movable base-indicators.

16. In a game apparatus of the character described comprising a bounded field area, a raceway having terminals in different horizontal planes but in the same perpendicular plane within said field area, movable base-indicators mounted at intervals along and transversely of said raceway when occupying normal position, but susceptible to movement away from said raceway, and movable actuators engaging and operating said movable base-indicators.

17. In a game apparatus of the character described comprising a bounded field area, a raceway having terminals in different horizontal planes but in the same perpendicular plane within said field area, movable base-indicators mounted at intervals along and transversely of said raceway when occupying normal position, but susceptible to movement away from said raceway, and movable actuators engaging to simultaneously operate one or more of the movable base-indicators.

In witness whereof I have hereunto set my hand and seal, at Indianapolis, Indiana, this 6th day of December, A. D. 1905.

EDWARD H. MILLER. [L. S.]
